DESIGN FOR A POCKET STEREOSCOPE

Harrison C. Ryker, Oakland, Calif.

Application June 28, 1940, Serial No. 93,299

Term of patent 14 years

To all whom it may concern:

Be it known that I, Harrison C. Ryker, a citizen of the United States and a resident of the city of Oakland, county of Alameda, State of California, have invented a new, original, and ornamental Design for a Pocket Stereoscope, of which the following is a specification, reference being had to the accompanying drawing, forming part thereof.

Figure 1 is a front view of a pocket stereoscope showing my new design;

Figure 2 is a top plan view, thereof; and Figure 3 is an end view of Figure 2, but with part of the temples broken away for convenience of illustration.

I claim:

The ornamental design for a pocket stereoscope, substantially as shown and described.

HARRISON C. RYKER.
